PROCESS FOR TREATING FATTY OILS

Don Sheldon Bolley, Brooklyn, and Edwin Charles Gallagher, Freeport, N. Y., assignors to National Lead Company, New York, N. Y., a corporation of New Jersey

No Drawing. Application October 18, 1945,
Serial No. 623,166

3 Claims. (Cl. 260—424)

1

This invention relates to improvements in methods of purifying and bleaching fatty oils.

Fatty oils are often treated prior to use with bleaching agents to remove coloring matter and certain other impurities. The bleaching earths employed for this purpose include adsorbent clay, bleaching clay, fuller's earth, and the like and in the bleaching treatment, these are mixed with the oil and allowed to remain in contact with the oil sometimes at an elevated temperature for varying periods of time. They are subsequently removed from the oil, for instance, by filtration or centrifuging, or in any other convenient manner. The coloring matter and other impurities are removed by direct adsorption on the clay.

Some fatty oils, particularly the drying oils used in the varnish industry, contain certain impurities such as phosphatides, which leave a residual ash when the oil is burned. These ash-forming substances, when present in an oil which is to be heat bodied, often cause either a precipitation during heating called "break," or excessive frothing. Hence it is desired to remove these ash-forming substances before the oil is heat bodied, and it has been found that they are adsorbed and removed by certain bleaching earths. The present invention constitutes a simple and effective means for removing the ash-forming material, coloring matter, and like impurities from fatty oils.

It is an object of the present invention to provide a method for producing fatty oils having a light color. Another object of the invention is to provide a method for producing fatty oils having a reduced ash content. A third object of the invention is to provide a method for producing fatty oils having a light color and a reduced ash content. These and other objects of the invention will become apparent from this description.

The present invention in its broadest aspect comprises first admixing a small amount of a strong mineral acid with a fatty oil and adding thereto a bleaching earth and after the bleaching earth has remained in contact with the oil for a desired period of time, removing the earth from the so treated oil.

By the term "strong mineral acid" as used herein is meant an inorganic acid which is practically completely ionized with respect to the first hydrogen. The preferred acid to use in the practice of the invention, from the point of view of freedom from reactivity with the oil, is sulfuric acid, but other mineral acids, such as hydrochloric, may be used provided that at the concentration employed, they do not react with the

2

oil. Nitric acid is not recommended because at practically all concentrations it reacts with the oil.

The invention may be employed for the treatment of fatty oils generally for the bleaching thereof and removal of ash-forming impurities, for example, fatty oils such as linseed, soybean, cottonseed, peanut, corn, olive, palm, perilla, castor and sardine oils. The bleaching earths useful in the practice of the invention are those commonly employed for bleaching fatty oils, e. g. the so-called adsorbent or bleaching clays, fuller's earths, and the like.

The improved results of the present invention are obtained within a wide range of acid concentration. The concentration should be selected to yield the optimum results without adverse effect, for instance, charring of the oil. Thus the concentration, especially for sulfuric acid, may vary between about 10% and about 75%, preferably between about 40% and 60%, say about 50%. The amount of acid to be employed may vary from 0.045% to about 5.0%, preferably between about 0.1% to about 2.0%, based on the weight of the oil treated. Inasmuch as the bleaching earth is removed from the oil the amount employed is of no particular consequence. Good results are obtained using as little as about 2.0% up to about 10%. In commercial operations about 2.5% is satisfactory; on a smaller scale about 5.0% may be used.

In practicing the invention the acid is added to the fatty oil and the mixture agitated for sufficient time to disperse thoroughly the acid in the oil, which generally takes from about two to about ten minutes, or longer if desired. Then the bleaching earth is added and the agitation is continued for a time, sufficient to reduce the ash content to a desired low limit, for instance from about ten minutes to about two hours, or even longer, if necessary. Elevating the temperature during the bleaching earth treatment tends to shorten the requisite time of treatment and enhance the improved results. Thus, it is desirable after adding the bleaching earth to raise the temperature of the batch to between about 90° C. and 120° C.

The following examples illustrate the invention without limitation.

50

EXAMPLE I

Procedure.—To 500 grams of raw linseed oil was added 0.25 per cent by weight of a 50 per cent solution of sulfuric acid in water. The oil and acid were agitated for about five minutes after

which the acid was thoroughly dispersed in the oil. Five per cent of a grade No. 1 bleaching earth (bleaching earths are graded according to their bleaching efficiency: grade No. 1=good; grade No. 2=medium; grade No. 3=poor) was added to the acid-oil mixture and while agitating, the temperature was raised to about 100° C. and held at that point for about ten minutes. The oil was then filtered to remove the bleaching earth. For purposes of comparison, the experiment was repeated omitting the acid treatment.

10

RESULTS
*Lovibond Wesson color*¹

	Red	Yellow	Percent Ash
Oil before treatment	3.3	30 (1 inch column)	0.112
Oil after treatment of Ex. I.	5.0	25 (5/4 inch column)	0.005
Oil acid treatment omitted.	5.5	30 (5/4 inch column)	0.05

¹ *The Lovibond Wesson color determination.*—The method and apparatus was adopted by the American Oil Chemists' Society on May 1941, as their official method. A description appears in the "Official and Tentative Methods of the American Oil Chemists' Society" revised to January 1, 1944.

EXAMPLE II

Procedure.—Same is for Example I, but substituting a grade No. 2 bleaching earth

RESULTS
Lovibond Wesson color

	Red	Yellow	Percent Ash
Oil before treatment	3.3	30 (1 inch column)	0.112
Oil after treatment of Ex. II.	8.5	55 (5/4 inch column)	0.018
Oil acid treatment omitted.	8.5	55 (5/4 inch column)	0.061

EXAMPLE III

Procedure.—Same as for Example I, but substituting a grade No. 3 bleaching earth.

RESULTS
Lovibond Wesson color

	Red	Yellow	Percent Ash
Oil before treatment	3.3	30 (1 inch column)	0.112
Oil after treatment of Ex. III.	12.6	60 (5/4 inch column)	0.018
Oil acid treatment omitted.	13.2	70 (5/4 inch column)	0.090

EXAMPLE IV

Procedure.—Same as for Example I, but substituting a refined cottonseed oil and using a grade No. 1 bleaching earth.

RESULTS
Lovibond Wesson color

	Red	Yellow	Percent Ash
Oil before treatment	1.8	20 (5/4 inch column)	0.000
Oil after treatment of Ex. IV.	0.9	10 (5/4 inch column)	0.000
Oil acid treatment omitted.	1.1	10 (5/4 inch column)	0.000

EXAMPLE V

Procedure.—Same as for Example I, but substituting a refined cottonseed oil and using a grade No. 2 bleaching earth.

RESULTS
Lovibond Wesson color

	Red	Yellow	Percent Ash
Oil before treatment	1.8	20 (5/4 inch column)	0.000
Oil after treatment of Ex. V.	1.1	12 (5/4 inch column)	0.000
Oil acid treatment omitted.	1.5	15 (5/4 inch column)	0.000

EXAMPLE VI

Procedure.—Same as for Example I, but substituting a refined cottonseed oil and using a grade No. 3 bleaching earth.

RESULTS
Lovibond Wesson color

	Red	Yellow	Percent Ash
Oil before treatment	1.8	20 (5/4 inch column)	0.000
Oil after treatment of Ex. VI.	1.4	15 (5/4 inch column)	0.000
Oil acid treatment omitted.	1.4	20 (5/4 inch column)	0.000

EXAMPLE VII

Procedure.—Same as for Example I, but substituting raw soybean oil and using a grade No. 1 bleaching earth.

RESULTS
Lovibond Wesson color

	Red	Yellow	Percent Ash
Oil before treatment	6.0	35 (1 inch column)	0.203
Oil after treatment of Ex. VII.	10.6	40 (5/4 inch column)	0.065
Oil acid treatment omitted.	14.8	55 (5/4 inch column)	0.082

EXAMPLE VIII

Procedure.—Same as for Example I, but substituting raw soybean oil and using a grade No. 2 bleaching earth.

RESULTS
Lovibond Wesson color

	Red	Yellow	Percent Ash
Oil before treatment	6.0	35 (1 inch column)	0.203
Oil after treatment of Ex. VIII.	15.0	55 (5/4 inch column)	0.093
Oil acid treatment omitted.	15.2	55 (5/4 inch column)	0.125

EXAMPLE IX

Procedure.—Same as for Example I, but substituting raw soybean oil and using a grade No. 3 bleaching earth.

RESULTS
Lovibond Wesson color

	Red	Yellow	Percent Ash
Oil before treatment	6.0	35 (1 inch column)	0.203
Oil after treatment of Ex. IX.	19.4	65 (5/4 inch column)	0.082
Oil acid treatment omitted.	28.0	70 (5/4 inch column)	0.126

The foregoing examples all clearly show the improved results of the present invention resulting from the conjoint action of a small amount of a strong mineral acid and a bleaching earth on various fatty oils. The following example demonstrates the superiority of the present invention over a procedure wherein the bleaching earth is heated with the acid.

EXAMPLE X

Procedure.—Same as for Example I, using raw linseed oil and a grade No. 1 bleaching earth. In the comparative treatment the acid was mixed with the bleaching earth and this mixture added to the oil. In other respects, the procedure, i. e. weights, time and temperatures were the same.

RESULTS

Lovibond Wesson color

	Red	Yellow	Per cent Ash
Oil before treatment	3.4	30 (1 inch column)	0.121
Oil after treatment of Ex. X.	5.6	20 (5/4 inch column)	0.005
Oil acid added to earth	6.6	35 (5/4 inch column)	0.039
Oil acid treatment omitted	6.6	35 (5/4 inch column)	0.036

The improved results of the present invention apply also to refined oils, such as acid refined linseed oil, as shown by the following example.

EXAMPLE XI

Procedure.—Same as for Example I, using an acid refined linseed oil.

RESULTS

Lovibond Wesson color

	Red	Yellow	Percent Ash
Oil before treatment	3.2	30 (1 inch column)	0.000
Oil after treatment of Ex. XI.	4.5	30 (5/4 inch column)	0.000
Oil acid treatment omitted	5.3	30 (5/4 inch column)	0.000

The use of hydrochloric acid in the practice of the present invention is illustrated by the following example which shows particularly the lowering of ash content.

EXAMPLE XII

Procedure.—Same as for Example I, but substituting 0.25 per cent, by weight of 18 per cent hydrochloric acid.

RESULTS

Lovibond Wesson color

	Red	Yellow	Percent Ash
Oil before treatment	3.0	25 (1 inch column)	0.153
Oil after treatment of Ex. XII.	5.6	30 (5/4 inch column)	0.032
Oil acid treatment omitted	4.4	30 (5/4 inch column)	0.099

From the foregoing description of the present invention, it will be obvious to those skilled in this art that the present invention is capable of considerable modification with respect to the variety of fatty oils to which it is applicable; with respect to bleaching earths and acid employed, and the like, all within the scope of the appended claims.

We claim:

- 20 1. A method for refining fatty oils which comprises admixing between about 0.045% and 5.0% by weight of sulfuric acid having a concentration between about 10% and 75% with an impure fatty oil, incorporating bleaching earth in the oil-acid mixture, heating it to a temperature between about 90° C. and about 120° C., allowing the oil to remain in contact with the acid and bleaching earth for a sufficient length of time to effect a refinement of the oil, and separating the so-treated oil from the bleaching earth.
- 25 2. A method for refining fatty oils which comprises admixing between about 0.1% and about 2.0% by weight of sulfuric acid having a concentration between about 40% and 60% to an impure fatty oil, agitating the mixture to disperse the acid in the oil, incorporating bleaching earth in the oil-acid mixture and, while agitating the mixture, heating it to a temperature between about 90° C. and about 120° C., and maintaining the mixture at that temperature for a sufficient length of time to effect a refinement of the oil, and separating the so-treated oil from the bleaching earth.
- 30 3. Method according to claim 2 wherein the fatty oil is raw linseed oil.
